VACUUM CLEANER

Frederick Riebel, Jr., and Dewey M. Dow, Toledo,
Ohio, assignors to Air-Way Electric Appliance
Corporation, Toledo, Ohio, a corporation of
Delaware

Application September 18, 1935, Serial No. 41,058

6 Claims. (Cl. 15—16)

This invention relates to vacuum cleaners of the type having a swinging handle and has for its object to provide in such a cleaner, an arrangement wherein the fan and rotary agitator are both driven from a motor of minimum height above the supporting surface on which the cleaner operates, and wherein the handle is positioned a substantial distance rearwardly of the suction nozzle so as to allow maximum projection of the nozzle under furniture, etc.

The invention further aims to combine these features in an arrangement wherein the fan case swings with the handle so that a paper bag may be supported below the handle and attached to the fan case outlet so as to be free of strains imposed by swinging of the handle.

The foregoing objects are realized by arranging the motor forwardly of the fan case, rearwardly of the suction chamber, and just above the throat connecting the fan case and suction chamber, which throat is carried rearwardly at a minimum height, and arranging the fan case to swing around the axis of the fan shaft, which is parallel to the axes of the motor and agitator, whereby untwisted driving belts may be employed. The dust collecting bag, of porous paper, is attached to the handle and to the fan case outlet, and the fan case is rigidly attached to the handle so that all three swing as a unit, and relative movement between fan case and bag is entirely eliminated.

Another object is to provide for ready accessibility to the motor and driving connections.

One embodiment of the invention is illustrated in the accompanying drawing, in which:

Fig. 1 is a side elevation, partly in section, of vacuum cleaner embodying the invention.

Fig. 2 is a horizontal sectional view taken on the line 2—2 of Fig. 1, and

Fig. 3 is a detail sectional view taken on the line 3—3 of Fig. 1.

Fig. 4 is a side elevation of the invention.

The invention provides a floor tool assembly A and a handle, fan case and bag assembly B. The former comprises a suction chamber 10, a throat 11 extending rearwardly therefrom, a pair of inlet ducts 12 communicating with the respective sides of the fan case 13, and with the rear extremity of the throat 11, and a motor 14 mounted on top of the throat 11.

The unit B comprises a handle 15, the fan case 13 rigidly secured thereto, the dust collecting porous paper bag 16 communicating with the fan case outlet 17, and the supporting envelope 18, enclosing the bag 16 and suspended below the handle on rods 19 defining a bag inserting mouth.

The unit A is supported on floor wheels 20 and 21, the former journaled in sockets 22 formed on the suction chamber 10, and the latter journaled on an adjustable bracket 23 pivoted to lugs on the ducts 12.

A fan case 13 has opposed inlets 25, which are in swivelling connection with the circular outlets 26 of the ducts 12. A double fan 27 operating in the fan case 13, is mounted on a shaft 28 which is journaled in bearings 29 in the ducts 12. 10

In the suction chamber 10 is a rotary agitator comprising a spindle 30 journaled in the ends of the chamber 10, and beating and brushing elements 31 and 32 respectively, mounted thereon. The spindle, the motor shaft 33, and the fan shaft 15 28 are parallel to each other, each lying horizontally transverse to the direction of movement of the cleaner. A pulley 34 on the spindle 30 is connected by a straight untwisted belt 35 to a pulley 36 on the motor shaft 33, and pulleys 37, on the 20 fan shaft 28, are connected by means of belts 38, to the pulleys 39 on the motor shaft 33.

The motor 14 is enclosed between the throat 11, and a cover 40 which is extended rearwardly and cut away, embracing the fan case 13, to form a 25 housing for the belts 38. The cover 40 is hinged at 41 to brackets 48 secured to the ducts 12 beneath the belts 38 so as to form guards therefor. A separate compartment for the belt 35 is formed by a partition 42 secured in the cover 40, its 30 lower edge fitting the contour of the upper surface of the throat 11 and adapted to seat thereagainst when the cover is in closed position.

The partition 42 has a slot 43 to accommodate the shaft 33 when the cover is raised, and a flap 35 44, its upper end sealed around the shaft 33, closes the slot 43. The lower end of the flap 44 is secured to the top wall of the throat 11.

The lower edges of the cover 40 are straight, and the throat 11 is built up around the depression 40 in which the motor 14 is seated forming a shoulder 45 to meet these edges. A flange 46 formed around the shoulder 45, receives the cover.

The motor is arranged to occupy the corner of 45 space between the fan case and the suction chamber, and is depressed below the upper extremities of both. This reduces the clearance height of the motor substantially below that of any cleaner of the motor driven agitator type 50 and gives a balanced drive to both fan and agitator.

The fan case, handle, and bag assembly swing as a unit around the axis of the fan shaft, so that strain on the neck of the bag is avoided.

5 The double fan receives air from both ducts 12, which communicate with the throat 11 at points disposed intermediate the longitudinal center of the suction chamber and its respective ends, so that a relatively high degree of equalization of suction in all regions of the suction chamber is obtained.

10 The ducts 12 are detachably secured at 50 to the throat 11, so as to allow detachment of the fan case.

15 The fan case has a peripheral lug 49 adapted to engage the underside of the throat 11 so as to support the suction nozzle in normal position when the cleaner is picked up bodily.

20 The motor 14 is an open frame motor, and the casing therefor is formed between the throat 11 and cover 40. The latter may be lifted to an upstanding position, giving access to the motor, both drive belts, and the connections between the ducts 12 and the fan case.

25 The throat 11 has a removable plate 11a forming its lower wall and its side walls and upper wall are formed integrally with the suction chamber 10.

30 The agitator belt 35 extends through a slot 47 in the top wall of the suction chamber 10. The invention is not to be limited to the exact construction illustrated and described, but is intended to be construed as covering all modifications thereof which come within the scope of, or are equivalent to, what is defined in the appended claims.

We claim as our invention:

35 1. In a vacuum cleaner, a suction chamber, a throat extending rearwardly therefrom, a rotary agitator in said chamber, a fan casing having a chamber therein, means whereby the chamber communicates with the said throat, a fan in said casing, its axis horizontal and transverse to the direction of movement of the cleaner, said fan casing being hinged to the suction chamber on the axis of said fan, a handle rigidly attached to the fan casing, a bag suspended below the handle and fixedly connected to the fan casing outlet, a motor disposed between said suction chamber and fan casing above the throat, and driving connections between said motor and the fan and agitator respectively.

40 2. In a vacuum cleaner, a suction chamber, a throat extending rearwardly therefrom, a fan casing having a chamber, means whereby the chamber communicates with the said throat, a fan in said casing, its axis horizontal and transverse to the direction of cleaner movement, said fan casing being hinged to the suction chamber on the axis of said fan, a handle rigidly attached to the fan casing, a bag suspended below the handle and fixedly connected to the fan casing outlet, a motor disposed between the suction chamber and the fan casing and above the throat, and driving connections between said motor and the fan, said motor and fan chamber both being centered in the vertical central longitudinal plane of the cleaner.

45 3. In a vacuum cleaner, a suction chamber, and a rotary agitator therein, a throat extending

5 rearwardly from said chamber whose upper surface is so constructed and arranged as to provide an available space therein, a fan casing, a fan therein, said fan and fan casing being centered in the central longitudinal vertical plane of the cleaner with their axes horizontal and transverse to the direction of cleaner travel, said fan casing being hinged to the chamber on the axis of said fan, a motor snugly occupying the available space between the fan casing and the suction chamber and above the throat and positioned below the level of the top of the fan casing, said fan casing being interiorly connected to said throat, and driving connections between the motor and the fan and agitator respectively.

10 4. In a vacuum cleaner, a suction chamber, a throat extending rearwardly from said chamber whose upper surface is so constructed and arranged as to provide an available space therein, a fan casing, a fan therein, said fan and fan casing being centered in the central longitudinal vertical plane of the cleaner with their axes horizontal and transverse to the direction of cleaner travel, said fan casing being hinged to the chamber on the axis of said fan, a motor snugly occupying the available space between the fan casing and the suction chamber and above the throat and positioned below the level of the top of the fan casing, said fan casing being interiorly connected to said throat and driving connections between the motor and the fan.

15 5. In a vacuum cleaner, a suction chamber, a throat extending rearwardly from said chamber whose upper surface is so constructed and arranged as to provide an available space therein, a fan casing, a fan therein, said fan and fan casing being centered in the central longitudinal vertical plane of the cleaner with their axes horizontal and transverse to the direction of cleaner travel, said fan casing being hinged to the chamber on the axis of said fan, a motor snugly occupying the available space between the fan casing and the suction chamber and above the throat and positioned below the level of the top of the fan casing, said fan casing being interiorly connected to said throat and driving connections between the motor and the fan.

20 6. In a vacuum cleaner, a suction chamber, a throat extending rearwardly from said chamber, a fan casing, a fan therein, said casing and fan being centered in the central longitudinal vertical plane of the cleaner with their axes horizontal and transverse to the direction of cleaner travel, said fan casing being hinged to the chamber on the axis of said fan, a motor disposed between the suction chamber and fan casing and above the throat and centered in said plane, said fan casing having an inlet on each side, each connected to the throat, and driving connections between said motor and the fan.
